ATTORNEYS

UNITED STATES PATENT OFFICE.

SYDNEY ALBERT, OF NASHVILLE, TENNESSEE.

COLLAR.

1,321,875.

Specification of Letters Patent. Patented Nov. 18, 1919.

Application filed June 16, 1919. Serial No. 304,462.

To all whom it may concern:

Be it known that I, SYDNEY ALBERT, a citizen of the United States, and a resident of Nashville, in the county of Davidson and 5 State of Tennessee, have invented certain new and useful Improvements in Collars, of which the following is a specification.

My invention relates to collars, and has reference more particularly to soft fold-collars wherein it is desirable to have the ends 10 of the folded-over top of the collar held closely to the band of the collar.

The main object of my invention is to provide means for holding a soft collar in 15 shape as to be form fitting.

Another object is to provide simple, cheap and efficient means whereby the ends of the folded-over top can be held closely to the band of the collar.

20 With these and other objects in view, my invention consists in certain novel features of construction, arrangement and combination of parts as will be hereinafter more fully described and pointed out in the claims, 25 reference being had to the drawing in which:

Figure 1 is a perspective view of a collar embodying my invention,

Fig. 2 is a plan view of one end of a 30 soft fold-collar embodying my invention with the inside of the top of the collar opened out,

Fig. 3 is a similar view of the other end of the collar.

Referring more specifically to the drawings, 35 5 is the band and 6 the top or fold-over of the collar, both of which may be made soft or not starched stiffly; the band and top are of a type very much used and well known to the public, the flap having the 40 button holes 7, 8, and 9 and the button 10.

The top member 6 is folded over on the band 5 along its line of attachment thereto in the usual manner.

In carrying out my invention, I secure to 45 the inner face of the top fold near one end a tape or strap 11 having at its free end a button engaging means such as a buttonhole 12; the other end of this tape may be attached to the fold by stitching or othersuitable means; 50 the buttonhole 12 is to fit over the usual front collar button B as will be later referred to, but other means for engaging the collar button may be resorted to. This tape or strap 11, it should be noted, has a normally horizontal extent, and at the other or 55 opposite end of the top fold 6, I propose to

provide a loop structure the opening thereof having a direction approximately perpendicular to the line of fold between the band and the top.

60

One method of securing such a loop is to stitch to the inside of the top adjacent the end thereof, a strip of flexible material 13, the stitching being done at the extreme ends 14, thus leaving a free space 15 between the strip and the inner face of the top fold 6 as plainly seen in Fig. 2, and it will be noticed that by this method of securing the loop that the tape or strip forming the same is disposed horizontally and that it is 70 located at about the longitudinal axis or center of the fold member 6; it will further be noticed that by so applying the strip that an elongated loop structure is secured so that the flat tape or strap 11 can readily 75 pass through the loop.

The tape or strap 11 is also flat and it is disposed at about the longitudinal axis or center of the top fold member 6, so that it will be in substantial horizontal alinement 80 with the loop element on the other end of the collar.

The operation is as follows:

The collar having been secured to the neck-band of the shirt by buttonhole, and 85 the front ends of the collar connected in the usual manner and secured to the front collar button B, the tape or strap 11 is drawn across the space between the ends of the collar over the front flap F beneath the opposite end of top fold and threaded through the loop, pulled downwardly and forwardly and the buttonhole 12 engaged with the front collar button B; this draws the ends 90 of the collar together and maintains them 95 in place and prevents the top fold 6 from bulging out of shape, and the collar from collapse by wilting.

The use of the strap 11 in no way interferes with the easy tying of a knot in the 100 necktie, and indeed the necktie conceals the strap and its connections from view when properly positioned.

If desired the loop strip may be evolved by making parallel horizontal slits slightly 105 spaced apart, in the inner layer of the top fold.

I claim:—

1. A fold-collar including a band member having a buttonhole adjacent one end 110 adapted to engage a collar button, a fold-over top member, a flexible tape or strap at-

tached at one end to and extending from the inner face of one end of said top member and having collar button engaging means at its free end, a horizontally disposed loop on the inner face of the opposite end of the said top member, said tape or strap adapted to be passed through said loop and then connected with the collar button by the button engaging means at its free 10 end.

2. A fold-collar comprising a band member having an end button hole, a fold-over

top member, a strap or tape secured at one end to the inner face of the folded top, adjacent one end and at approximately its longitudinal center, said strap having collar-button engaging means at its free end, and a flat strip horizontally disposed and rigidly secured at its ends to the inner face of the opposite end of the fold top and in horizontal alinement with the aforesaid tape or strap. 15 20

SYDNEY ALBERT.
